UNITED STATES PATENT OFFICE.

JAMES M. VAUGHAN, OF OWENSBORO, KENTUCKY.

TOBACCO-TREATING MACHINERY.

1,017,713.

Specification of Letters Patent.

Patented Feb. 20, 1912.

Application filed April 23, 1911. Serial No. 623,478.

To all whom it may concern:

Be it known that I, JAMES M. VAUGHAN, a citizen of the United States, residing at Owensboro, in the county of Daviess and 5 State of Kentucky, have invented certain new and useful Improvements in Tobacco-Treating Machinery, of which the following is a specification.

This invention comprehends certain new 10 and useful improvements in tobacco treating machinery, and relates particularly to an improved construction of apparatus of the continuous type, the parts of which are so arranged that the tobacco, fed into one 15 end of the machine, may be carried continuously therethrough so as to be dried by the action of heated air, subsequently cooled to the required temperature, and finally "ordered" by the action of jets of live 20 steam.

The invention has for one of its objects an apparatus of this character in which the heated air may be maintained at all times at a predetermined or requisite temperature, 25 in which said air may be kept pure and thereby assist in producing a better product, and in which the air will have extracted therefrom the particles of nicotin taken up from the tobacco and held in suspension, this not only keeping the air pure, but saving this valuable by-product.

With this and other objects in view as will more fully appear as the description 30 proceeds, the invention consists in certain 35 constructions, arrangements and combinations of the parts that I shall hereinafter fully describe and claim.

For a full understanding of the invention, 40 reference is to be had to the following description and accompanying drawings, in which:

Figure 1 is a longitudinal vertical sectional view of the feed end or portion of a tobacco treating apparatus embodying the 45 principles and improvements of my invention; Fig. 1^a is a similar view of an intermediate portion of the machine; Fig. 1^b is a corresponding view of the discharge end or portion of the machine; Fig. 2 is a vertical transverse sectional view, the section being taken substantially on the line 2—2 of Fig. 1, looking in the direction of the arrows; Fig. 3 is a detailed sectional view 55 on the line 3—3 of Fig. 1^b; Fig. 4 is a plan view of that portion of the apparatus which

is shown in longitudinal section in Fig. 1^a; and, Fig. 5 is an end view opposite to the end illustrated in Fig. 2.

Corresponding and like parts are referred to in the following description and indicated in all the views of the drawings by the same reference characters.

Extending longitudinally in the main framework or housing of the apparatus are any desired number of endless chain carriers 1, the number thereof depending, manifestly, upon the size of the plant or apparatus, there being three pairs of these carriers in the present embodiment of the invention (see Fig. 2). The chain carriers 65 1 embody hooked links, the hooks being designated 2 and being designed for engagement with sticks 3 extending transversely as shown and on which the bunches of tobacco 70 may be suspended.

Within the upper and lower stretches of the several chain carriers 1, an endless foraminous or reticulated carrier 4 is mounted, preferably extending for a longitudinal movement from one side of the gang 75 of chain conveyers to the other. In the present instance, the conveyer 4 is made or built up of any desired number of laterally joined strips of woven wire. The upper stretch of the conveyer 4 lies next to and 80 below the upper carrying stretch or stretches of the endless chain conveyers 1, as clearly illustrated in Fig. 1, and is primarily designed to support and carry along loose leaves or portions thereof that may be 85 broken or dropped from the bunches suspended on the sticks 3, although it is of course to be understood that the tobacco, in its loose leaf or other condition, may be laid directly upon the upper stretch of the conveyer 4.

The main housing or framework of the apparatus includes a bottom wall 5 which may be the floor of the room in which the apparatus is located, longitudinally extending 100 vertical side walls 6, a main or top roof 7, and partition or lower false roof 8 which, with inner or false side walls 9, divide the housing from one end to the other into a main middle compartment A 105 and side compartments B which are designed for the circulation of heated air and in which steam radiators 10, or other heating devices, are mounted. The side compartments B communicate at the lower edges 110

of the inner false side walls 9 with the bottom of the main middle compartment A and communicate with a top compartment C which is separated from the top of the compartment A by means of the false roof 8. The false roof 8 is formed with any desired number of openings 11 spaced at any desired intervals longitudinally thereof and in each of these openings there is mounted a down-draft fan 12 suspended to rotate about a vertical axis on the lower end of a vertical shaft 13, said shafts extending up through the top or main roof 7 and being driven in any desired way, as by bevel pinions 14 meshing with corresponding pinions 15 on a main line or drive shaft 16 extending in a median line along the top of the roof 7 and journaled in any suitable bearings. In this connection, it is to be understood that while Figs. 1 and 1^a show different portions of the drying portion of the apparatus, such portions are not continuous in the accompanying drawings; for the sake of brevity and to reduce the number of sheets of drawings used, an intermediate portion of the drying part of the apparatus has been omitted. Suffice it to say that this portion of the apparatus may be of any desired length and embody any desired number of the down-draft fans 12 arranged at any desired distances apart. At this point, I deem it advisable to describe for the sake of clearness, the operation of producing circulation of heated air in the drying portion of the machine. It will be seen that the fans 12 serve to create or maintain a circulation of air downwardly from the top chamber C onto and through the tobacco carried by the conveyers 1 and 4, and that such air currents, after passing through and acting upon the tobacco and through the upper stretch of the conveyer 4, will be deflected outwardly and thence pass upwardly through the side compartments B in which the heaters 10 are located, the air being thereby properly heated. These downwardly, outwardly, upwardly, and then inwardly moving currents of air are gradually drawn toward the feed end of the machine, the means in the present instance for accomplishing this action comprising up-draft or suction fans 17 that are two in number in the present instance and that are mounted at the top of an up-draft chamber or compartment D separated from the compartment C by a transversely extending vertically disposed partition 18. In the present embodiment of the invention, the up-draft fans 17 are driven by transverse countershafts 19 that have a common driving connection with the shaft 16 at one end of the latter.

It is here to be particularly noted that the fans 17 are interposed between the outlet opening 20 of the up-draft compartment D

and any desired number of coils 21 of any desired number of convolutions, said coils separating the fans from the final discharge passage 22 which leads to the atmosphere and which may be provided with any desired form and construction of damper 23. In the present instance, the damper is controlled by means of a cord 24 connected at one end thereto and leading downwardly to a point within convenient reach of the attendants. It is intended that cold water shall be circulated through the coils 21, being passed thereto from a supply pipe 25 and discharged therefrom through a pipe 26, on opposite sides of the machine. Hence, as the air, heavily laden with nicotin, is sucked up from the compartment D and caused to pass through the coils 21 through which the cold water is flowing, the nicotin will be condensed and fall into laterally extending pans or troughs 27 which in the present instance are two in number extending in opposite directions as best seen in Fig. 2, the nicotin, which is a valuable by-product for a variety of uses well known to those skilled in the art to which this invention appertains, being thereby collected and saved, while at the same time the air is purified, which not only promotes hygienic conditions in the room in which the apparatus is located, but also insures a purer and sweeter product in the treated tobacco, this result being secured by means which I shall now describe.

Leading rearwardly from the coils 21 are any desired number of flues 28, these being two in number in the present instance in order to provide a middle space on the roof 7 for the accommodation of the line shafting and other driving parts. By closing the damper 23, the entire volume of air passed through the coils 21 may be caused to flow through the flues 28, said flues terminating in and covering openings 29 that are formed in the top 30 of the middle cooling chamber E of the machine. A main fan 31 is mounted in the chamber E, said fan being a down-draft fan and drawing the air from the flues 28 down into the main middle compartment A above the upper stretch of the chain 1. Thus a continuous circulation may be maintained, the air being purified repeatedly as it passes through the coils 21, this operation also insuring that the proper temperature may at all times be maintained, as by actuating or adjusting the damper 23 or any desired number of dampers 32 arranged at any desired intervals apart at the upper ends of the compartment B above the heating coils or radiators 10, the dampers 32 being controlled in any desired way, as by cables 33.

34 designates doors that are provided in the opposite side walls 6, whereby the condition of the different compartments, that is,

the temperature thereof, and the condition of the tobacco may be determined at any time.

Referring now more particularly to Figs. 5 1^a and 1^b which are intended to represent continuous portions of the machine, it will be noted (see Fig. 1^a) that the compartment E borders upon the "ordering" or discharge portion of the apparatus. The 10 main middle compartment A and the side compartment B and top compartments C are all included in this portion of the apparatus, the false roof 8 which separates the middle compartment A from the top compartment C being formed with any desired 15 number of openings 35 in which down-draft fans 35 are mounted, said fans being carried by vertical shafts 37 operatively connected to the main line shafting 16^a which 20 corresponds to and which is arranged in longitudinal alinement with the shafting 16 before mentioned. The shaft 31^a which carries the fan 31 is also operated by the shafting 16^a, and it is to be particularly noted that the two lines of shafting 16, 16^a are 25 separately driven as by belts 38 from a main drive shaft 39, independently operable clutches 40 being connected with the band wheels 41 for the driving belts 38, whereby 30 one line of shafting may be driven and the other held in an inoperative position, according to the particular requirements of the case. The tobacco, as it passes through this rear portion of the machine, is acted 35 upon by air heated by live jets of steam passing inwardly into the compartment A at the bottom thereof from heaters 42 that are mounted in pockets 43 constructed on the outer side of the main housing or frame- 40 work, the steam passing through orifices 44 formed in the side walls of the housing, as best illustrated in Fig. 3. The air is circu- 45 lated, by means of the down-draft fans 36, down through the tobacco and is, laden with the live steam, thence passed upwardly and inwardly so as to maintain a lateral circulation, while at the same time these air currents are drawn toward the rear end of the machine by any desired number of 50 up-draft fans 45 secured to shafts 46 and operatively connected to the line shafting 16^a. The fan or fans 45 force the air into flues 47 that open at their forward ends into the compartment C adjoining the compartment E. At intermediate points in their length, the flues 47 are formed with cold air intake passages 49 controlled by dampers 50, and at other points in their length, for instance, at their rear ends, said 55 flues 47 are formed with steam exhaust passages 51 controlled by dampers 52 operated by means of cables or cords 53. It will thus be understood that if conditions in the ordering compartment justify it, I might 60 not wish to exhaust steam or take in cold 65

air, in which event both dampers 50 and 52 would be closed, thus allowing the steam drawn up from the fans 45 to be carried on over the top of the machine through the fans and recirculated by means of the first 70 fan in the ordering room or compartment next to the cooling fan 31. Or, the damper 52 may be opened to any desired extent so as to permit steam to exhaust and the damper 50 may be opened to any desired extent 75 according to conditions present or requirements of the case, so as to exhaust some of the steam and take in fresh air.

As the operations of the different parts of the apparatus have been described in connection with the construction and operation thereof, I deem no further description of the operation necessary.

The conveyers may, of course, be driven in any desired way, that is by any desired 85 mechanism. In the present embodiment of the invention, they are driven only at the rear or discharge end of the apparatus, the drum shaft 56 for the rear end of the conveyer 4 carrying a sprocket wheel 57 which is connected by a sprocket chain 58 to a corresponding wheel 59 on the rear shaft 60 of the upper stretch of the conveyer 1. This shaft 60 also carries a worm gear 61 which meshes with a worm 62 on the lower end of 90 a vertically disposed shaft 63, it being of course understood that there are three of these shafts 63 and related parts, owing to the fact that there are three pairs of endless chain conveyers 1. Each of the shafts 100 63 carries at its upper end a worm gear 64, said gears meshing with worms 65 on a shaft 66, which receives its motion from a stub shaft 67 driven as by a belt 68 from a driving shaft 69 supported in suitable hangers 105 from the ceiling of the room.

When the tobacco is laid directly upon the upper stretch of the conveyer 4, and not suspended from the sticks on the conveyer 1, I preferably employ end doors 70, at both 110 ends of the machine, said doors being swung downwardly to partially inclose the ends of the housing above the upper stretch of the conveyer 4 and the spaces between the adjoining side edges of the door being closed 115 by laterally swinging sections 71.

It is to be understood that my invention is not limited to the use of cold water pipes to produce the condensation of the nicotine, but that any cold surface may be employed 120 for this purpose; and that various other changes may be made in the construction, arrangement and proportions of the parts without departing from the scope of the invention as defined in the appended claims. 125

Having thus described the invention, what is claimed as new is:

1. An apparatus of the character described, embodying a compartment for the tobacco, means for establishing a circula- 130

tion of heated air through the compartment, and means for condensing the nicotin from the circulating air.

2. An apparatus of the character described, embodying a compartment for the tobacco, means for establishing and maintaining a circulation of heated air in said compartment, and a nicotin condenser mounted in said compartment in the path of the current of air.

3. An apparatus of the character described, embodying a compartment for the tobacco, means for maintaining a circulation of heated air in said compartment, said means including down-draft fans, a flue connected at its ends to the compartment, a nicotin condenser in said flue, and an up draft fan interposed in said flue between the condenser and the communicating end of the compartment.

4. An apparatus of the character described, comprising a compartment for the tobacco, a flue connected at its ends to the compartment, the flue being provided with

a damper controlled discharge passage, a nicotin condenser interposed between said passage and the adjoining end of the compartment, and means for establishing a circulation of air through the flue and compartment, said air passing through the condenser.

5. An apparatus of the character described, embodying a compartment for the tobacco, a flue connected at its ends to the top of the compartment, said flue being provided with a damper controlled discharge passage, a nicotin condenser comprising cold water pipes mounted in said flue, a trough underneath said pipes, and means for establishing a circulation of heated air through the flue and compartment.

In testimony whereof, I affix my signature in presence of two witnesses.

JAMES M. VAUGHAN. [L. s.]
